EDWIN H. BAARE, OF ST. LOUIS, MISSOURI, ASSIGNOR TO WILLIAM J. LEMP BREWING COMPANY, OF ST. LOUIS, MISSOURI, A CORPORATION OF MISSOURI.

PROCESS OF AFFIXING LABELS.

No. 830,195.

Specification of Letters Patent.

Patented Sept. 4, 1906.

Application filed January 8, 1906. Serial No. 294,987.

To all whom it may concern:

Be it known that I, EDWIN H. BAARE, a citizen of the United States, residing at the city of St. Louis, State of Missouri, have invented certain new and useful Improvements in Processes of Affixing Labels, of which the following is a specification.

This invention relates to improvements in processes of affixing labels, especially those of peculiar or irregular shape. A separate application for patent for one form of machine for practicing said process was filed by me July 21, 1905, Serial No. 270,609, and is copending herewith.

In the accompanying drawings, forming part of this specification, in which like numerals of reference denote like parts wherever they occur, I have illustrated such machine so far as is necessary to aid in understanding my said process.

Figure 1 is a top plan view of one form of machine for practicing my herein-described process; and Fig. 2 is a vertical sectional view on the line 2 2, Fig. 1.

Bottlers and other persons have long desired to attract special notice for their goods by using a label which from some distinct, irregular, and peculiar shape would enable the public to recognize and identify their goods by the shape of the label alone, and thus give a means of distinguishing them from those of other manufacturers in addition to the matter printed on the label. While numerous labels of distinctive shape have been designed, great difficulty has been experienced in applying them in commercial quantities to the articles to which they are to be attached, and while they might be affixed by hand that process is much slower and far more expensive than the methods practiced by machines. While some processes have been devised for affixing regularly-shaped labels, most of them are not adapted for use when it is desired to handle labels of irregular or peculiar shape.

My new process of applying labels consists in placing the labels to be affixed in a suitable receptacle, which I prefer to call a "label-stock holder," then separating the top label from the stock of labels, the separation being accomplished by pneumatic action, carrying the individual label so separated by any suitable means, which I speak

of as a "label-carrier," to a predetermined point, retaining same on the carrier means by pneumatic action till the predetermined point is reached, treating said individual label with adhesives while being so retained, cutting off the pneumatic action and thereafter or simultaneously stripping the individual label from the carrier at the proper time, forwarding the label to a predetermined point while loosely resting upon or while loosely held by the forwarding means, allowing said forwarding means to support the label by coming into contact with a very limited portion of its surface, the label resting on said forwarding means by gravity while being so forwarded, stripping the label from its said supporting and forwarding means at said predetermined point, causing the same thereupon to be supported by other means adapted to hold both the label and the bottle, and then causing the bottle by gravity and other impulsion to roll over the gummed label thus supported, the label by means of the weight and movement of the bottle, assisted, if necessary, by other pressure, being thus caused to adhere to the bottle.

In order to render the foregoing description of my said process more intelligible, I will briefly describe one form of machine by which it can be practiced and the operations thereof.

The main frame 1, consisting of certain vertical standards and horizontal cross-pieces 2, supports in their several positions the various moving parts hereinafter described. The arrows indicate the direction of movement or rotation of said moving parts. A common source of power-supply—for instance, the belt 3—directly or indirectly actuates all said moving parts. The belt 3 drives the band-wheel 4, keyed to the main shaft 5, to which is also fixed the grooved pulley 6, which drives the grooved pulley 7 by the belt 8, said pulley 7 being fixed to the shaft 9, which rotates the roller 10, said shaft 9 being journaled in suitable bearings 11 on the receptacle 12, which holds the adhesive material 13, applied to the labels by the roller 10, during the course of its rotation.

The main shaft 5, journaled in one of the cross-pieces 2, drives a pinion 14, fixed at its inner end. The same cross-piece, with a

similar one on the opposite side of the machine, also provides bearings for other shafts 15 and 16. The shaft 16 is stationary and hollow, the hub 17 of the wheel 18 encircling 5 same and revolving therearound, the spokes 19 connecting the rim of said wheel 18 to the hub 17. An additional pair of hollow spokes 20 communicate with the interior of the shaft 16 and also with the dies or label-holders 21, which contain a plurality of perforations 22, thereby effecting communication between the exterior atmosphere and the interior of the shaft 16 for purposes to be hereinafter described. A slot 23 is formed 15 circumferentially partially around the wheel of shaft 16 opposite the openings of the hollow spokes 20, so that when the wheel 18 is revolved on shaft 16, the slot 23 opens into the hollow spokes 20 part of the time, while 20 the part of the circumference of shaft 16 opposite said slot 23, said part being marked 24, acts as a cut-off of communication between the interior shaft 16 and one of the hollow spokes 20 during that part of the 25 travel of die 21 when same is approaching its highest point. From the hollow shaft 16 a pipe or tube 25 leads to any suitable fan, (not shown,) so that as the fan operates it creates suction successively through pipe 25, 30 shaft 16, slot 23, spokes 20, and perforations 22, so that when a label is upon one or both of the dies or label-holders 21 said air-suction retains it in that position, except that as a spoke 20 passes the uncut-away portion 35 24 the air is thereby blocked off from that spoke 20. Thus during the major portion of the rotation of the label-carrier 18 air-suction takes place through the perforations 22 and spokes 20. The shaft 16, by means of 40 the slot 23 therein, thus acts as a valve allowing air-suction the greater part of the time, but cutting off the same during that part of the rotation of one of the spokes 20 when the die 21 is nearing the upper position 45 in Fig. 2, the pneumatic action being cut off at that time in order to facilitate the stripping of the label from the die 21, as herein-after described.

To the wheel 18 is fixed concentrically the 50 gear 26, which meshes with and is driven by the pinion 14. The rotation of the wheel 18 carries the dies or label-holders 21 successively past the label stock located in the label-cup 27, the adhesive-applying roller 10, and to 55 the point where the label is stripped from the label-holder 21, which point is at the position of the upper label-holder 21, as shown in the drawings. The die 21 and cup 27 operate as coacting male and female parts 60 when the die 21 in the course of rotation of the wheel 18 has reached such point of its travel that it can enter the cup 27. As the wheel 18 further rotates, the die 21 is withdrawn from the cup 27 and passes on the 65 roller 10. Within the cup 27 is placed a

stock of labels resting on the plate 28, which is arranged by suitable mechanism to move forward as the stock of labels is exhausted. The cup 27 is mounted on arms 29, pivoted by the shaft 30 to one of the cross-pieces 2, and a pitman 31 is pivoted eccentrically to said arm 29 and is also pivoted eccentrically at 70 32 to the pinion 14, so that as the pinion revolves it alternately depresses and raises the cup 27. These oscillations are so timed and 75 regulated that the cup 27 opens at just the right time and in the right position to receive each one of the dies 21 and to allow them to enter and leave without friction. When the wheel 18 rotates so as to cause one 80 of the dies 21 to enter the cup 27, the die compresses the stock of labels, consisting of a large number of individual labels, so as to express the air from between the same and drive it out of the cup through the perforations 33 formed in the mouth thereof or along the sides of the stock of labels and of die 21. This leaves the stock of labels like a solid block, and allows the suction of air through the perforations 22, hollow spokes 20, slot 23, shaft 16, and pipe 25, induced by the fan 85 aforementioned to separate a single label from the pile constituting the stock, which label is then held by the air-suction just referred to upon the dies 22, which are fastened in any suitable manner, so as to pass through the rim of the wheel 18 and form an air-tight connection with the hollow spokes 20. When the label has been separated from the stock by the pneumatic action, as 90 above described, and while said label is still retained on the label-holder 21 by the same pneumatic action, the rotation of the wheel 18 carries the label from the cup 27 past and usually in direct contact with the paste-roller 10, whereby a coating of adhesive is 95 applied on the side of the label that goes next the bottle. Suitable spring-fingers 34 are properly mounted to keep the label from adhering to the paste-roller 10. 100

In the periphery of the wheel 18 (elsewhere denominated the "label-carrier") a plurality of grooves 35 is provided, which grooves extend through the dies 21. Endless steel wires or threads 36 are located in said grooves and 115 pass around grooved pulleys 37, which rotate on shaft 38. As the wires are located between the label and the rim of the wheel 18, they are adapted to strip the label from the dies 21 as said dies reach the point of tangential departure of said wires 36 from the wheel 18, the pneumatic action being cut off by the uncut-away portion 24 of the shaft 16 just as the label reaches said point. Then as the rotation of the wheel 18 actuates the endless wires 36 to travel as endless conveyors they 120 serve as a conveyer for each of the labels from the time said wires strip the labels from the wheel or label-carrier 18, conveying each label individually to the labeling-table 39. The 125 130

labeling-table 39 has grooves 40, which receive the wires 36. Said table 39 is vertically movable, and each label conveyed by the wires 36 reaches a point immediately above same at a time when said table 39 is in its lower position. The forward movement of the label on the wires 36 is limited by a pin 41, which is placed in a recess in table 39, said recess containing a spring 42, which normally projects the pin 41 above the table 39, so as to stop the labels when brought into contact therewith by the wires 36, but allows depression of said pin within said recess by the mere force of the bottles rolling over the same. The table 39 has depending therefrom standards 43, which support the same. The table preferably consists of a metal plate 44, said plate having on its edges a flange 45, which retains a rubber pad or block 46 in place, thus giving the table a cushion-like character when the bottles roll upon it.

A pair of cams 47, revolving with the shaft 15, which is driven by the pinion 14, meshing with a gear-wheel 48, fixed to said shaft 15, produces the vertical reciprocation of the table 39. The standards 43, working in the sleeves 49, formed in the hanger 50, depending from one of the cross-pieces 2, have roller-bearings 51 at their lower ends. Said rollers 51 ride in the grooves 52 of the cams 47, and when in the course of rotation of the cams 47 the rollers 51 strike the shoulders 53 they ride over the same, thus instantly causing the table 39 to rise, and the same remains in its higher position so long as the rollers 51 ride on the high part of the cams 47. Above the table 39 extends the endless conveyer 54, consisting of a flat belt or web traveling over a pair of pulleys 55, journaled by horizontal shafts 56, which are supported in any convenient manner by the arms 57 and bracket 58. The function of the endless conveyer 54 is to cause the bottles to travel across the labeling-table 39 until the bottle leaves the table 39 and having been labeled thereon rolls upon the shelf 59, from whence it can be removed to be packed and shipped.

Before being labeled the bottles 60 are placed on the inclined shelf 61, and an escapement 62 (shown only in part in these drawings) allows the bottles to roll one at a time down the shelf 61, across the table 39, where it receives its label, and onto shelf 59. In addition to the rolling motion imparted to the bottle by the said incline it is also positively fed forward by the movement of the endless conveyer 54, which serves also as a means for pressing the label more tightly upon the bottle as the same travels between the conveyer 54 and the table 39. The upward vertical movement of the table 39 takes place at the very moment that the bottle lands upon said table, and the bottle rolling on said table depresses the pin 41, so as to leave a free roll-

ing-surface for the bottle across the table. 65 The withdrawal of said pin 41 does not affect the label which has been delivered by the wires 36 against and stopped by said pin 41; but the label is left lying on the rubber pad 46 of the table 39, being disengaged from the 70 wires 36 by the upward vertical movement of the table 39, said movement causing the wires to descend to the lowest portion of the grooves 40 in the table 39. This neatly separates the wires 36, which have conveyed the 75 label to that spot from said label even if the wires have become sticky from long use. By this means the label is left in a position exactly in the path of travel of the bottle across the labeling-table and detached from anything that might hold it, and the bottle by gravity—that is to say, by its mere weight rolling upon the label—causes the label to adhere to it and wrap about it, said adhesion being promoted and tightened and the over-plus adhesive material expressed by the pressure of the conveyer 54 and pad 46 upon the label and bottle. 80 85

Near the end of shaft 15 is attached the bevel-gear 63. This meshes with another 90 bevel-gear 64, attached to shaft 65, on which shaft is keyed a sprocket-wheel 66. Over this wheel 66 passes a chain 67, which actuates the wheel 68, keyed to a shaft, (not shown,) which shaft passes through the 95 sleeve 69 and drives a pulley 70, attached to said shaft to actuate the endless conveyer 54. At the end of shaft 15 is a pinion 71, which actuates the escapement device by means of gear 72, shaft 73, sprocket 74, chain 75, and 100 shaft 76.

The operation of the machine is as follows: All parts move in the direction indicated by arrows. The fan, having been started, induces air-suction through the pipe 25, hollow shaft 16, slot 23, hollow spokes 20, and perforations 22 in the dies 21. The receptacle 12 for the adhesive material with which the label is to be pasted upon the bottle having been previously filled with such adhesive, preferably in liquid form, the main shaft 5, by means of belt 8 and pulley 7, rotates roller 10, the label-stock holder 27 having been filled with labels to a point adjacent to or slightly beyond the circumferential perforations 33, the disk 28 being at the bottom of the cup 27. With the rotation of the main shaft 5 the pinion 14 drives the gears 26 and 48 and with them the wheel or label-carrier 18 and the shaft 15. The wheel 18 thus successively presents each die or label-holder 21 at the mouth of the label-stock holder 27 and slightly inserts the same therein. For convenience of this insertion and also to enable the label-holder 21 to compress the stock of labels within the cup 27, expressing the air between the labels through the perforations 33 or alongside the pack of labels, and to sepa-

rate the top label from the stock of labels and remove same from the label-stock holder or cup 27 without the removed label coming in contact with the edges of the cup 27 said 5 cup 27 is given an oscillating movement by alternate depression of the pitman 31, eccentrically connected at 32 to the pinion 14. The label-holder 21 leaves the cup 27, holding a label thereon, which is carried by the 10 further revolution of the wheel or label-carrier 18 until said label comes into contact with the roller 10, where the label receives a coating of adhesive material. The wheel 18 thereupon continues its rotation and carries 15 the gummed label to the point where the wires 36 act as a stripping device and themselves assume the functions of a label-conveyer to carry said label from the wheel 18 to the table 39, where the label is positioned by 20 the pin 41, projecting above said table 39. Thereupon the table 39 vertically rises, stripping the label from the wires and bringing the table first into a plane with the shelf 61 and later into a higher position, where the 25 bottle is pressed between the table 39 and conveyer 54, the label being thus caused to adhere tightly to the bottle which is forwarded by the conveyer 54 to the shelf 59, thence to be removed. The high position of 30 the table 39 is maintained until the bottle has traveled across the same and has reached the shelf 59. Thereupon the table descends to its lowest position, this alternate rising and falling movement of the table 39 being 35 produced by the rotation of the cams 47, fixed to the shaft 15, which is driven by the gear 48, meshing with pinion 14. The rollers 51 ride upon the cams 47 and being connected with the standards 43, supporting the 40 table 39, cause said table to rise and fall. The supply of bottles to the table 39 is regulated and predetermined by the speed of the escapement devices 62, actuated by shaft 15, and the conveyer 54 is also actuated by said shaft by means of gears 63 64, 45 sprocket-wheel 66, and the shaft in sleeve 69. All of the moving parts are so proportioned, arranged, and regulated that they move synchronously, so that each shall perform its 50 proper function at the proper time to coöperate with any other and all parts depending thereupon. Thus the label-holders 21 are so arranged with relation to the other parts that a label is delivered to the table 39 at a time 55 when the upward movement of the table will act to strip the label from the wires 36 and also at such time with relation to the escapement of the bottles that the bottles will cause the labels to adhere thereto by rolling there- 60 over. In like manner the oscillation of the label-stock holder is so regulated that its opening registers with the approaching die or label-holder 21 and continues in register therewith until an individual label has been 65 secured by the label-holder and until the la-

bel-holder 21 has rotated so as to be withdrawn from the label-stock holder 27.

Having thus described my said invention, what I claim, and desire to secure by Letters Patent, is—

1. The herein-described process of labeling bottles and the like consisting in separating an individual label from a stock by pneumatic action, retaining same thereby, treating said individual label with an adhesive 75 while thus retained, and carrying same by means of said pneumatic action to a point adjacent where the weight and movement of the bottle cause said label to adhere to the bottle, and affixing said label to a bottle by 80 causing the bottle so to move with relation to said label that the weight and movement of the bottle cause the adhesion of the label thereto.

2. The process of applying labels to bottles or like objects consisting in picking up an individual label by pneumatic action and retaining same by the same means, treating same with an adhesive on one side while so held, and continuing said pneumatic action 90 until the label is carried adjacent the bottle to be labeled, then stripping the label from said pneumatic retainer, then forwarding same in a plane immediately underneath the labeling position of the bottle, and then causing the bottle to roll over the label, whereby 95 the label adheres to the bottle.

3. The process of applying labels to bottles or like objects consisting in carrying a label by pneumatic action and otherwise to a 100 predetermined point, applying adhesives to the label while being carried thereto, applying pressure from below at said predetermined point, and then allowing the bottle to roll over the label, whereby the weight and movement of the bottle, assisted by the pressure from below cause said label to adhere to the bottle.

4. The process of applying labels to bottles and the like consisting in separating an individual label from a stock by pneumatic action, retaining same thereby, treating said individual label with an adhesive while thus retained, carrying same by pneumatic action 110 a predetermined distance, stripping the label 115 from the pneumatic carrier, and carrying the label loosely to a predetermined point, and at said predetermined point causing the weight and movement of the bottle to produce adhesion of said label to the bottle.

5. The process of applying labels to bottles and the like consisting in separating an individual label from a stock by pneumatic action, retaining same thereby, treating said individual label with an adhesive while thus 125 retained, carrying same by pneumatic action a predetermined distance, stripping the label from the pneumatic carrier, and forwarding the label while supported by partial contact with its surface to a predetermined point, 130

and at said predetermined point causing the weight and movement of the bottle to produce adhesion of said label to the bottle.

6. The process of applying labels to bottles consisting in stripping a gummed label from a carrier means on which it has been held by pneumatic action by cutting off the pneumatic action and immediately thereafter or simultaneously removing same from the carrier means, forwarding the label while loosely held on the forwarding means to a

predetermined point, and at said predetermined point causing the weight and movement of the bottle to produce adhesion of said label to the bottle.

15

In testimony whereof I have affixed my signature in presence of two witnesses.
